UNITED STATES PATENT OFFICE.

GEORGE R. RICH, OF BATTLE CREEK, MICHIGAN.

TAPPET FOR INTERNAL-COMBUSTION ENGINES.

1,339,421.

Specification of Letters Patent.

Patented May 11, 1920.

Application filed January 10, 1917. Serial No. 141,661.

To all whom it may concern:

Be it known that I, GEORGE R. RICH, a citizen of the United States, and a resident of Battle Creek, county of Calhoun, and 5 State of Michigan, have invented certain new and useful Improvements in Tappets for Internal-Combustion Engines, of which the following is declared to be a full, clear, and exact description.

10 This invention relates to tappets for internal combustion engines, and its principal object is to provide improved means for silencing the noise or clicking sound produced from the striking of the tappet 15 against the valve stem of the engine. To those skilled in the art to which this invention pertains, it is well known that a slight clearance is left between the tappets and valve stems of internal combustion engines, 20 in order that the valves may be free to seat upon the valve seats during the compression and explosion strokes of the piston. The clearance space is slight but when the parts become worn this space increases and the 25 noise or clicking sound becomes more noticeable and annoying. In the present device, the tappet and valve stem are kept in constant contact, and the clearance space is provided in the tappet itself where a comparatively 30 large bearing surface is provided for the contacting of the two relatively movable members of the tappet, and where oil or other lubricant is maintained to lessen the noise and shock.

35 The invention consists in the several novel features clearly set forth in the following specification, and more definitely pointed out in the appended claims.

The invention is clearly illustrated in the 40 accompanying drawing, in which:

Figure 1, is a view, partly in side elevation and partly in central vertical section through an engine body, and puppet valve mechanism, showing a tappet embodying a 45 simple form of the invention; Fig. 2, is a cross section of the tappet taken on line 2-2 of Fig. 1; and Fig. 3, is a view, partly in side elevation and partly in vertical section, of a slightly modified form of the invention.

50 Referring to said drawing and first to Figs. 1 and 2, the reference numeral 4, designates a fragment of the valve casing and 5, designates a fragment of the body of an 55 internal combustion engine of common and well-known construction. In accordance

with the common practice, a puppet valve 6, controls the passage-way through the casing and is yieldingly held upon a seat 7, by a compression spring 8, encircling the valve 60 stem 9, of the valve, and bearing against a washer, secured upon the valve stem. A cam shaft 10, having a cam 11 thereon, is employed as usual for lifting the tappet 12, and therewith unseating the valve. The 65 tappet is slidably held in a bearing 13, carried by the engine body 5.

In its preferred form, the tappet comprises a tubular body portion 14, which slides in the bearing 13, and conveniently it 70 may be formed with a disk-like head 15, or other bearing member that bears against the cam 11. In its preferred form, the bore of the tubular body portion, near its upper 75 end, is of larger diameter than at its lower end to provide an annular shoulder or slot 17, and slidably secured in the enlarged part of the bore is an internally screw threaded tubular member 18, the lower end of which is adapted to contact with the shoulder 17, 80 during the lifting movements of the tappet. A spring, preferably a coiled compression spring 19, is interposed between the lower closed end of the tubular member 18, and the bottom of the bore, for supporting the tubular member away from said shoulder while the tappet rides on the low part of the cam. 85

Adjustably mounted in the bore 16, of said tubular member is a valve engaging and lifting member, here shown in the form of a 90 bolt 20, threaded in the tubular member 8, and having a set nut 21, threaded thereon, which bears against the tubular member 18, and fixedly locks the bolt 20, and member 18, together. Said member 18 has flattened 95 sides 22, at its upper end to accommodate a wrench when adjustment is necessary. The parts are so adjusted that when the valve is seated, and the low part of the cam is in contact with the tappet, a slight clearance space is left between the lower end of the tubular member 18, and the shoulder 17; the set nut 21 is then screwed down 100 tight against the tubular member 18. It is understood that the spring holds the head 20^a of the bolt 20 in constant contact with the lower end of the valve stem 9, and also yieldingly holds the lower end of said member 18 out of contact with the shoulder 17. 105

The clearance space between the tubular member 18, and shoulder 17, permits the valve to seat while the low part of the cam 110

contacts with the tappet. When the cam begins to lift the tappet, the shoulder 17, strikes the lower end of the tubular member 18, and thereupon the tappet body lifts the tubular member, and therewith the bolt 20, and valve 6. The shoulder 17, of the tappet body is held in contact with the tubular member until the low portion of the cam approaches the tappet, and until the valve has 10 become seated, whereupon the tappet body moves down until it reaches the low part of the cam, the spring 19, yieldingly supporting the tubular member 18 away from the shoulder 17, and therewith holding the bolt 20 in contact with the valve stem, thus eliminating the noise.

The modified form of the invention shown in Fig. 3, is intended for use in internal combustion engines which employ overhead 20 valves and actuating mechanism. therefore. In this form of the invention, a valve actuating rocker-arm 23, is shown, which is lifted by a cam (not shown) that bears against the tappet body 12, as in the preferred form. Said tappet body is bored as in the preferred form, and a tubular member 18^a, is slidably secured in the bore and spring 25 pressed away from the shoulder. In the bore of the tubular member 18^a, is a rod 24, which rests upon the bottom of the bore 16^a, and the top of said rod is adjustably connected with the rocker arm 23, by a bolt 20^b, threaded in an internally screw threaded socket formed in the upper end of the rod, 30 24 and rockably connected to the rocker arm 23, by hinged joint or universal joint as is well known to those skilled in this art. A set nut 26, locks the bolt and rod together. The adjustment for obtaining the desired 35 clearance space between the tubular member 18^a, and shoulder 17^a, of the tappet body is obtained with the bolt 20^b, which may be screwed up or down in the socket of the rod 24.

40 45 More or less variation of the exact forms

of construction of the invention shown and described is possible without departing from the spirit of this invention; I desire, therefore, not to limit myself to the exact forms shown but intend in the following claims to point out all of the invention disclosed herein.

I claim as new, and desire to secure by Letters Patent:

1. A tappet for internal combustion engines comprising a centrally bored tappet body, having a cylindrical bearing surface throughout the major portion of its length, the bore at the upper end being enlarged to provide an internal annular shoulder and being closed at the bottom, a tubular member sliding in the upper enlarged part of the bore of said tappet body with its lower end in close proximity to, and arranged to seat upon said shoulder, a coiled compression spring in the lower part of said bore and confined between the bottom of said tubular member and bottom of the bore and acting to unseat said tubular member, and a valve lifting member held in said tubular member. 55 60 65 70

2. A tappet for internal combustion engines comprising a centrally bored tappet body, having a cylindrical bearing surface throughout the major portion of its length, and having a closed end adapted to be directly engaged by suitable actuating means, the bore at the upper end of said tappet body being enlarged to provide an internal annular shoulder, an internally screw threaded tubular member in the upper enlarged 75 80 85 part of said bore, the lower end of which is in close proximity to, and arranged to seat upon said shoulder, a coiled compression spring in the lower part of said bore confined between the bottom of said tubular member and bottom of the bore and acting to unseat the tubular member, and a valve lifting bolt, threaded in said tubular member.

GEORGE R. RICH.
